UNITED STATES PATENT OFFICE.

JOSEPH H. CHAMP, OF CLEVELAND, OHIO.

BOTTLE-HOLDER FOR BOTTLE-FILLING MACHINES.

1,017,038

Specification of Letters Patent. Patented Feb. 13, 1912.

Application filed September 21, 1911. Serial No. 650,489.

To all whom it may concern:

Be it known that I, JOSEPH H. CHAMP, a citizen of the United States, and a resident of Cleveland, county of Cuyahoga, and State of Ohio, have invented a new and useful Improvement in Bottle-Holders for Bottle-Filling Machines, of which the following is a specification, the principle of the invention being herein explained and the best mode in which I have contemplated applying that principle, so as to distinguish it from other inventions.

In automatically feeding bottles onto the holders or lifts of bottle filling, or like, machines by mechanism of the kind described, for example, in my co-pending application filed Feb. 15, 1911, Serial No. 608,787, difficulty is apt to be experienced, both in accurately centering the bottles on their respective holders, and in preventing their falling off. This is especially true in handling pints or bottles of smaller size, since such bottles, filling rapidly as they do, require to be fed likewise rapidly, and furthermore, such smaller bottles having correspondingly smaller bottoms are less steady and more apt to topple over, when forcibly transferred from the feeding mechanism onto the holders or lifts.

The object of the present invention, accordingly, is the provision of a bottle holder, or lift, which will serve not only to accurately guide the bottle into a properly centered position, but also steady the same so as to prevent the second of the difficulties noted above.

To the accomplishment of the foregoing and related ends, the invention, then, consists of the means hereinafter fully described and particularly pointed out in the claims.

The annexed drawing and the following description set forth in detail certain mechanism embodying the invention; such disclosed means constituting, however, but one of various mechanical forms in which the principle of the invention may be used.

In said annexed drawing:—Figure 1 is a perspective view of a bottle lift, or holder, with a bottle in place thereon, such holder embodying my present improvements; Fig. 2 is a vertical sectional view of the same; and Fig. 3 is a plan view of a portion of a feeding mechanism, showing several bottle holders of the present improved construction in operative relation thereto.

The bottle feeding mechanism is, of

course, of incidental interest only, and may be of any suitable construction, the one illustrated being fully described in the co-pending application hereinbefore identified. In such mechanism, the bottles are brought up to the feeding station by suitable conveying means 1, being guided by means of ribs 2, 2 to a point where they may be transferred, 65 one by one, onto successive bottle holders of the filling or other machine. The transferring of the bottles is automatically controlled by a pivotal gate 3 operated by such holders, such gate being normally swung inwardly 70 from the position illustrated in Fig. 3 by a tension spring 4, so as to interrupt the movement of the bottles between the guides. Upon the gate being properly positioned, the pressure on the line of bottles will force 75 the foremost one off the table 5, which supports the mechanism just described, onto the adjacently positioned holder. This holder is in general of familiar form, consisting of a flat plate 6 on the upper end of a depending stem 7, which is connected with the operating mechanism (not shown) that raises the holder to filling position. The rear edge of the plate, that is the edge disposed 80 radially inward in the case of a rotating machine as the one in hand, is curved and provided with an upwardly extending flange 8. This flange also extends along one adjacent lateral edge of the plate so as to form 85 a pocket into which the bottom of the bottle is forced and thus centered on the holder. The form and location of this flange are such as to thus receive and center bottles of quart size and with these, as previously explained, not so much trouble is experienced as with 90 the pint size, although means may be provided, if desired, for holding such bottles also.

In order to adapt the aforesaid holders for the reception of pint bottles and to retain such bottles in proper position thereon, the additional member illustrated in the several figures of the drawing is provided. This member consists of a tubular support 9 adapted to fit over a rod 10 mounted on 100 the holder, such support carrying at its lower end a curved flange 11 that is adapted to fit just within the flange 8 on said holder; while, at its upper end, said support is formed with a laterally projecting arm 12 110 from which extend forwardly in a substantially horizontal plane, two fingers 13 and 14. The flange of said support, when in place reduces the free space on the holder

plate to the proper size and form to receive the bottom of a pint bottle and the two fingers on the arm will then be disposed so as to engage the upper portion of the bottle as indicated in Figs. 1 and 2. The disposition of these fingers 13 and 14 with relation to the feeding mechanism is such that they serve, in a way, as extensions of the guides of such feeding mechanism when taken in conjunction with gate 3, the rearmost finger 14 being longer than the other so as to prevent the bottle being tipped over with its neck behind such finger.

By means of the foregoing mechanism, the transfer of the bottles, even of pint size may be effected with considerable rapidity without there being any tendency for the bottles to tip over or joggle on the holders, which if not actually leading to their falling off, will at least frequently displace them to such an extent as to render their filling impossible.

Where it is desired to employ similar guiding and receiving fingers for the quart size of the bottles, the flange 11 at the lower end of the support 9 will simply be omitted and the disposition of the arm 17 and fingers 13 and 14 varied to properly locate such size of bottle. As the change in construction thus required will be readily apparent, it has not been deemed necessary to additionally illustrate the same.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the class described, the combination with a bottle-holder including a plate provided with a lateral flange adapted to engage the bottom of a bottle and properly locate the latter; of a rod rising vertically from said holder; and a member adapted to detachably engage said rod, said member being provided at its upper end with fingers arranged to engage the upper portion of such a bottle.

2. In mechanism of the class described, the combination with a bottle-holder including a plate provided with a lateral flange adapted to engage the bottom of a bottle and properly locate the latter; of a rod rising vertically from said holder; and a member adapted to detachably engage said rod, said member being provided at its upper end with an arm extending horizontally over said holder and having two diverging fingers arranged to engage the upper portion of such a bottle.

3. In mechanism of the class described, the combination with a holder for relatively large bottles including a plate provided with a lateral flange adapted to engage the bottom of such a large bottle and properly locate the latter; of a rod rising vertically from said holder; and a member adapted to detachably engage said rod, said member being provided at its lower end with a flange adapted to fit within the aforesaid flange and reduce the space on said holder plate, and at its upper end with fingers arranged to engage the upper portion of a relatively small bottle.

4. In mechanism of the class described, the combination with a holder for relatively large bottles including a plate provided with a lateral flange adapted to engage the bottom of such a large bottle and properly locate the latter; of a rod rising vertically from said holder; and a member adapted to detachably engage said rod, said member being provided at its lower end with a flange adapted to fit within the aforesaid flange and reduce the space on said holder plate, and at its upper end with an arm extending horizontally over said holder and having two diverging fingers arranged to engage the upper portion of a relatively small bottle.

5. In mechanism of the class described, the combination of bottle feeding mechanism including guide-means; a bottle-holder including a plate provided with a lateral flange adapted to engage the bottom of a bottle and properly locate the latter when transferred from said feeding mechanism to said holder; and a member supported vertically above said holder and provided with fingers arranged to engage the upper portion of such a bottle, said fingers forming, in effect, continuations of said guide-means when said holder is adjacent said feeding mechanism.

6. In mechanism of the class described, the combination of bottle feeding mechanism including guide-means; a bottle-holder including a plate provided with a lateral flange adapted to engage the bottom of a bottle and properly locate the latter when transferred from said feeding mechanism to said holder; and a member supported above said holder and provided with diverging, horizontally extending fingers arranged to engage the upper portion of such a bottle, said fingers forming, in effect, continuations of said guide-means when said holder is adjacent said feeding mechanism.

Signed by me this 19th day of September, 1911.

JOSEPH H. CHAMP.
